ABSTRACT OF THE DISCLOSURE

A method of and an apparatus for applying two-part double bolster buttons of synthetic material connected together by a stay-part, and two-part hollow rivets or the like equipped with bolster buttons and serving as a stay-part in bolsters, mattresses, cushions and the like, which comprises the steps of strongly compressing and rigidly clamping a bolster about the position of a double bolster button, and punching the bolster at the point of the bolster button to be inserted. A small tube slides over the shaft of a mandrel behind cutting edges of the mandrel and the latter is withdrawn through the small tube and the mandrel and is removed from the bolster. A stay-part of one portion of the double bolster button or of a hollow rivet is inserted into the small tube on the side remote from the mandrel. The small tube is then withdrawn and the other portion of the double bolster button or the rivet equipped with a bolster button slides and is secured onto the first portion of the bolster button already in the bolster, and the clamping of the bolster is released.

The present invention relates to a method of and an apparatus for providing bolster double buttons and the like in bolsters, mattresses and cushions, in general, and of such two-part bolster-double buttons of synthetic material connected together by means of a stay-part and of two-part hollow rivets and the like equipped with bolster-buttons and serving as a stay-part, in bolsters, mattresses, cushions and the like.

For the securing of bolsters, mattresses, cushions and the like, two buttons are used now which are sewn together from both sides to the bolster, whereby the sewing threads form a stay between the two buttons. This stay holds the bolster filling and mattress filling, respectively, securely at its place and causes the bolster- and mattress-cover, respectively, to be non-displaceable. This stay had to be sewn manually until now. The bolster buttons to be applied should not outwardly show the thread and no possibility exists to sew this stay by machine.

One is dependent upon the sewing of this stay, because it is extremely difficult, to insert a stay of stronger material than the sewing thread into the bolster. Attempts to punch holes into the bolster with conventional means, which permit the passing through of a stay, did not operate. One requires extremely great forces, in order to project through the bolster, and the ram which is used easily deviates from its direction due to different resistances. Also the pushing through of bolsters with needles, which are stronger than 6 mm., is extremely difficult. Here also, forces are required, which are greater than the forces which are conventional in normal machines. The needle easily deviates from its direction. Thus, an apparatus, which presses together the bolster for this punching and retains it, must comprise a ring with a large inner diameter. This large inner diameter of the ring causes, however, on the other hand, that the bolster is prebulged on the side opposite the needle and attempts to avoid the

needle. This escape displaces the bolster, so that the created hole does not run straight. If finally such a strong needle is punched through the bolster, it must be withdrawn again for the insertion of the stay. During the withdrawal, 5 the bolster closes again and it is no longer possible, to insert a prefabricated stay into the prepared hole. Other attempts were made to punch the hole by means of a small tube formed to a cutting edge at its end face. These attempts also failed, because, here also, the bolster material, 10 and in particular more or less all types of material, and first of all, however, synthetic foaming material and artificial fiber wadding (nylon, perlon, dralon, etc.) try to eliminate the punching by bowing out.

These difficulties are the reason, why today bolster buttons are still sewn on by hand.

It is one object of the present invention, to provide a method of and an apparatus for the provision of bolster double buttons and the like in bolsters, mattresses and cushions, which provide a simple possibility to arrange holes of a larger diameter in bolsters and to insert into these holes stays for bolster buttons which are prefabricated without difficulty.

These stays for bolster buttons can be made either of two parts of synthetic material, whereby each part is produced integrally with one of the two bolster buttons, and they could be also hollow rivets, which are likewise made of two parts, and of which each part is rigidly connected with one of the two bolster buttons. Two such bolster buttons connected by stay parts are connected to a bolster double button such, that the two stay parts slide into each other, whereby these two stay parts lock automatically, by interengaging arresting devices provided thereon or the parts of the hollow rivet are riveted together.

It is another object of the present invention, to provide 35 a method of and an apparatus for the provision of bolster-double buttons and the like in bolsters, mattresses and cushions, wherein the bolster is strongly pressed together and rigidly clamped about the position of the bolster button, the bolster being punched through by means of a 40 mandrel having a plurality of cutting edges at the point of the bolster button to be inserted, a small tube being moved through the punched opening behind the cutting edges of the mandrel over the shaft of the mandrel, the mandrel being withdrawn through the small tube and removed 45 from the bolster, the stay part of one portion of the bolster button, hollow rivet or the like sliding into the small tube on the side remote from the mandrel, and the small tube is withdrawn and then the other part of the double bolster button or the rivet equipped with one bolster button slides 50 on and is secured to the first part already in the bolster, whereupon the clamping is released.

If one proceeds in this manner, and if one uses a pointed mandrel equipped with cutting edges, it is possible to 55 punch bolsters of conventional strength or thickness already with small forces.

Preferably, one uses a mandrel which has at least three cutting edges. In such mandrel of a diameter of 7.5 mm., one requires by example only a force of 12 kg. for the 60 punching of bolsters of foam of synthetic material of a thickness of 10 cm. By the following small tube, the sliding of which requires only very small forces, the hole is kept free even after the withdrawal of the mandrel, so that one can slide in without any effort the stay-part secured to the one bolster button and after the withdrawal 65 of the small tube from the bolster, this stay-part sits in the bolster and this stay-part projects from the bolster at the side remote from the bolster button, so that the application of the bolster button on this stay-part can be performed without any difficulty.

By this arrangement, a simple and non-objective application of bolster buttons of particular structure is

made possible. The draw-backs of manual labor can be avoided completely thereby.

It is still another object of the present invention to provide an apparatus for providing of bolster-double buttons and the like in bolsters, mattresses and cushions, which apparatus comprises a clamping device compressing strongly the bolster about the position of the bolster button and clamping rigidly the latter, a pointed mandrel having cutting edges and punching the bolster at the position of the bolster button to be inserted, a small tube displaceable over the shaft of the mandrel, a holder for the one part of the bolster button displaceable in the moving axis of the mandrel towards the small tube and rigidly clampable, and a holder for the second part of the bolster button swingable into the moving axis of the mandrel and displaceable for the sprinkling of the other bolster button part in the moving axis thereof.

Preferably, the mandrel has three cutting edges. The cutting edges are then well sharpenable, the created hole is sufficiently large and does not show the tendency, to tear out in one direction.

It is suitable that the clamping device for the bolster is made of two parts and attacks from both sides of the bolster. By this arrangement, it is brought about, that the bolster distribution after the clamping is quite unitary, so that the mandrel deviates only slightly from its direction during its penetration into the bolster.

It is of advantage, if for the clamping device for the operation of the mandrel, for the operation of the small tube, and for the operation of the displacement- and rotary-movement of the holder for the bolster button parts hydraulic or pneumatic operating means are provided. In particular, pneumatic operating means are of advantage, because it is suitable, to equip the button holders and the button feeders with connections to suction conduits, because such connections on suction conduits assure a safe securing of the bolster button parts or the like on the button holders and the button feeders. Upon use of a pneumatic arrangement, one obtains then with the same pump unit the pressurized air as well as the suction air.

It is also suitable to provide a follow control for the clamping of the clamping device, for the penetration movement of the mandrel or the simultaneous or following displacement movement of the small tube for the return movement of the mandrel, for the displacement of one button holder towards the small tube, for the return movement of the small tube and the simultaneous follow up movement of the first bolster button part, for the swinging movement of the second bolster button holder into the movement axis of the mandrel, for the advancement movement of the second button holder towards the first button holder, for the return movement of the button holder, as well as for the operation of the button feeder. One can design this follow control such, that in known manner at the end of each path of the individual working means a limit switch is provided, which releases the start of the movement of the following operating means which successively enters the operation. It is, however, also possible to provide in known manner a switching roller, which in timed succession successively runs off the individual movement processes.

With these and other objects in view, which will become apparent in the following detailed description, the present invention, which is shown by example only, will be clearly understood in connection with the accompanying drawings, in which:

FIG. 1 is an elevation, partly in section, of an apparatus, shown schematically, and designed in accordance with the present invention;

FIG. 2 is a fragmentary showing of the apparatus of FIG. 1, namely the clamping device as well as the operating means for punching of the hole and the insertion of the bolster double button in section prior to the starting of the operation;

FIG. 3 is a fragmentary elevation similar to that shown in FIG. 2, however, during the first step of the operation, namely the clamping of the bolster;

FIG. 4 is a fragmentary elevation similar to that shown in FIG. 2, disclosing the second step of the operation, namely cutting of the hole in the bolster;

FIG. 5 is a fragmentary elevation, similar to that shown in FIG. 2, disclosing the third step of the operation, namely the after-sliding of the small tube;

FIG. 6 is a fragmentary elevation, similar to that shown in FIG. 2, disclosing the fourth step of operation, namely the withdrawal of the mandrel;

FIG. 7 is a fragmentary elevation of the device, similar to that of FIG. 2, disclosing the fifth step of the operation, namely the insertion of the stay and of the one bolster button into the small tube and the bolster;

FIG. 8 is a fragmentary elevation, similar to that shown in FIG. 2, disclosing the sixth step of the operation, namely the withdrawal of the small tube;

FIG. 9 is a fragmentary elevation, similar to that shown in FIG. 2 disclosing the seventh step of the operation, namely swinging in of the holder of the second bolster button part into the axis of the movement path of the mandrel;

FIG. 10 is a fragmentary elevation, similar to that shown in FIG. 2, disclosing the eighth step of the operation, namely the displacement of the holder of the second bolster button part and anchoring in the stay of the first bolster button part;

FIG. 11 is a fragmentary elevation, similar to that shown in FIG. 2, of the ninth step of the operation, namely withdrawal of the button holder;

FIG. 12 is a fragmentary elevation, similar to that shown in FIG. 2, disclosing the tenth step of the operation, namely the release of the clamping device;

FIGS. 13a and 13b are axial sections of the two parts comprising the double bolster button; and

FIG. 14 is a perspective fragmentary view showing a preferred mandrel having three cutting edges.

Referring now to the drawings, a table 2 and a bow 3 are held in a machine frame 1. The bow 3 carries at its lower end a clamping device 4a, operated by a hydraulic or pneumatic means 4a; while the table 2 on the opposite side has a complementary clamping device 4b. The clamping device 4b can be omitted in simpler structures, in which case the bolster is retained between the table 2 and the clamping device 4a. With this clamping device 4a, the bolster member 5 is clamped prior to start of the operation of the apparatus, designed in accordance with the present invention. Below the table 2 is arranged a mandrel 6, which has several cutting edges at its point. This mandrel 6 is moved vertically upwardly in connection with the machine shown in the drawings by means of a pneumatic cylinder 9. A small tube 8 is disposed slidably over the mandrel, which small tube 8 is fortified in downward direction and driven by the piston of the pneumatic cylinder 9 and thereby the pneumatic drive 7 is retained in the upper end position for reception of the button part disclosed in FIG. 13b and upon receipt of the button part 13b, the small tube 8 is displaced into the lower end position.

In a simpler embodiment, the small tube 8 can be joined with the mandrel in the advancing direction, by example by means of a set off on the mandrel and inside of the small tube 8 and thereafter can be retained and moved back by conventional means.

With the mandrel 6 which is equipped with cutting edges, preferably three cutting edges 6' as shown in FIG. 14, the bolster 5 is punched through and either thereafter or simultaneously, the small tube 8 is moved upwardly through the bolster 5. By this arrangement it is possible to insert after withdrawal of the mandrel 6a, stay 21 of the bolster button 20 through the small tube 8 into the bolster 5. This takes place such, that the button holder 10 is moved downwardly by the pneumatic cylinder 11.

after the mandrel 6 has been withdrawn from the bolster 5. If the button 10 reaches its lower position, the small tube 8 can be withdrawn, so that the stay 21 sits in the bolster 5. By means of the rotary drive 12, the arm 14, carrying the second button holder 13, swings in after the return movement of the mandrel 6 and the small tube 8 into the axis of the movement path of the mandrel 6, and, after it has reached the axis, is pushed upwardly by means of the pneumatic cylinder 15, so that the second button part 23 with its stay projection 22 penetrates the stay part 21 of the bolster button 20, which is retained in its position by the button holder 10 by means of the pneumatic cylinder 11 filled with pressurized air. On a console 16 a button feeder 17 is provided which, by means of a multiple pneumatic cylinder 18 can be moved into the movement path of the button holder 10, so that the button holder 10 can receive, by means of pressure below atmospheric pressure a button part transported on the face 19. A similar feeder is provided for the button holder 13, however, not shown, since due to the swinging movement 20 of the arm 14, this feeder is disposed behind the plane of the drawing. Also, one or a plurality of abutments 25 with switches are provided, which start the operation by means of a follow control upon engagement of the bolster member equipped with the double bolster button.

Conduits 24, 24b, and 24c are provided for feeding pressure below atmospheric pressure to the button holders 10 and 13 and the feeding device 17, respectively.

In FIGS. 2 to 11 the individual steps of the operation of the machine are disclosed. The last step, namely the 30 release of the bolster member from its clamping position, is shown in FIG. 12.

FIGS. 13a and 13b show the double bolster button to be worked on the machine. It is to be understood, however, that also other buttons can be worked, as long as 35 the same have only two telescope-like stay parts capable of being put into a locking position by sliding into each other. The bolster button 20 is disposed on a stay part which is formed tubular-like and has means for the locking in form grooves, flutes or threads, while the stay part 40 of the bolster button of FIG. 13 is formed pin-like and has projections extending into the grooves, flutes or threads.

The machine is successfully used in the working of bolsters, mattresses, cushions, inserts, garden furniture 45 attachments, etc.

While I have disclosed one embodiment of the present invention, it is to be understood that this embodiment is given by example only and not in a limiting sense.

I claim:

1. A method of applying two-part double part bolster-buttons of synthetic material connected together by a stay-part, in bolsters, mattresses, cushions, comprising the steps of
  - strongly compressing and rigidly clamping from both sides a bolster about the position of a double part bolster button to be inserted,
  - sliding a small tube over the shaft of a mandrel behind cutting edges of said mandrel,
  - punching a hole in said bolster at the point of said bolster button to be inserted by insertion therethrough of said mandrel and tube,
  - removing said mandrel through said small tube and leaving said small tube in said bolster,
  - inserting a hollow stay-part of one part of said double part bolster button into said small tube from the side remote from said mandrel,
  - removing said small tube,
  - sliding on and securing the other portion of said double part bolster button into said stay-part of said one part of said bolster button already in said bolster, and
  - releasing the clamping of said bolster.
2. The method, as set forth in claim 1, wherein

10

25

45

50

55

60

65

75

- said step of punching said bolster is performed simultaneously with said mandrel and said small tube.
3. An apparatus for applying of double part bolster buttons of synthetic material, in bolsters, mattresses, cushions, comprising
    - a clamping means for compressing, strongly clamping said bolster from both sides about the position of a bolster button to be inserted,
    - a pointed mandrel including a shaft and having cutting edges and punching said bolster at the point of said bolster button to be inserted,
    - a small tube displaceable over said shaft of said mandrel,
    - a first holder for one part of said double part bolster button displaceable in the direction of movement of said mandrel towards said small tube, and
    - a second holder for the other part of said double part bolster button swingable to and away from the axis of movement of said mandrel and displaceable in the axis of movement of said other part of said double part bolster button for the insertion of the latter.
  4. The apparatus, as set forth in claim 3, wherein said mandrel has three cutting edges.
  5. The apparatus, as set forth in claim 3, wherein said clamping device for said bolster comprises two parts and engages said bolster on opposite sides.
  6. The apparatus, as set forth in claim 3, which includes hydraulic or pneumatic operating means for the operation of said clamping means, for the operation of said mandrel, for the operation of said small tube and for the operation of said holders, respectively.
  7. The apparatus, as set forth in claim 3, which includes a feeding device for said bolster button to said holders.
  8. The apparatus, as set forth in claim 7, which includes conduits for feeding pressure below atmospheric pressure to and connected with said holders and said feeding device, for holding said parts of said bolster button.
  9. The apparatus, as set forth in claim 7, which includes means for the operation of said clamping means, means for the punch movement of said mandrel, means for the displacement movement of said small tube,
  - means for the return movement of said first holder towards said small tube and the simultaneous follow up movement of said one part of the said bolster button,
  - means for the swinging movement of said second holder into the axis of movement of said mandrel,
  - means for the advancing movement of said second holder towards said first holder,
  - means for the return movements of said holders, and means for the operation of said feeding device.
  10. The apparatus, as set forth in claim 3, wherein said second holder is simultaneously swingable and axially displaceable.
  11. The apparatus, as set forth in claim 10, wherein said mandrel and tube are displaceable away from said bolster to a position such that said second holder can swingably move said other part of said bolster button into coaxial alignment with, and for insertion into, said one part of said bolster button when the latter is inserted in said bolster.
  12. The apparatus, as set forth in claim 3, wherein said first holder positions said one part of said bolster button into said bolster,
  - said second holder inserts said other part of said bolster into cooperative securing engagement with said one part of said bolster button,
  - said one part and said other part of said bolster button in the securing engagement with each other have the same appearance from both sides of said bolster, and said clamping means and said holders operatively cooperating to insert said one part and said other part of said bolster button, respectively, in said bolster

in symmetrical arrangement relative to a longitudinal plane through the middle of said bolster.
